[57] CLAIM

The ornamental design for a body suit, as shown and described.

DESCRIPTION

FIG. 1 is a front elevational view of a body suit showing my new design, the broken lines are for illustrative purposes only and form no part of the invention;

FIG. 2 is a side elevational view thereof, the opposite side being a mirror image thereof;

FIG. 3 is a rear elevational view thereof; and,

FIG. 4 is a perspective view thereof.
